UNITED STATES PATENT OFFICE.

JOHN F. A. HOORT, OF NEW YORK, N. Y.

DESIGN FOR A MANTEL.

SPECIFICATION forming part of Design No. 24,153, dated March 26, 1895.

Application filed January 10, 1895. Serial No. 534,495. Term of patent 3½ years.

To all whom it may concern:

Be it known that I, JOHN F. A. HOORT, a citizen of the United States, residing at New York, in the county of New York and State 5 of New York, have invented and produced a new and original Design for Mantels; and I do hereby declare the following to be a full, clear, and exact description of the same, reference being had to the accompanying drawing, forming a part thereof.

The figure of the drawing is an isometric view of the mantel.

The leading feature of the design is the design for mantel supports.

15 Numeral 1 indicates the mantel shelf consisting of an entablature comprising among other features a frieze ornamented with basket work. Two pairs of columns are denoted by 2. These have capitals 3 provided with foliated 20 ornaments and surmounted by a capital common to two of said columns and to a rectangular column 5. A pedestal for these is denoted by 6. The capitals 4 are ornamented with rosettes 7. In a deep recess between the capitals 4 and immediately beneath the basket work frieze are two panels 8. Between these and in advance of them is a larger panel 9 ornamented with a rayed figure 10 situated be-

tween two pendants 11 and surmounting a figure 12 having numerous terminal scrolls. The 30 panel 9 is bounded below by a beaded band extending between the capitals of the inner columns 2.

The mantel shelf is surmounted by a second entablature 13 having a lattice work frieze 14. 35

15 indicates two pairs of columns each pair having a capital 16 provided with a ring like ornament 17. Between these capitals is a sunken panel ornamented with a festoon and vines. This panel is bounded below by a basket work band 17 which is continuous with a band around the capitals, said capital bands being ornamented with festoons. Below the bands and between the columns is a panel 40 form 18.

The whole mantel has a skirt or background 19.

What I claim is—

The design for a mantel herein shown and described.

In testimony whereof I affix my signature in presence of two witnesses.

JOHN F. A. HOORT.
